SPARK PLUG

Original Filed July 26, 1929

UNITED STATES PATENT OFFICE

JOHN W. PULLIAM, OF OAKLAND, KENTUCKY, ASSIGNOR OF FIFTY PER CENT TO
WARNER D. HINTON, OF OAKLAND, KENTUCKY

SPARK PLUG

Application filed July 26, 1929, Serial No. 381,245. Renewed February 13, 1932.

This invention relates to improvements in spark plugs.

The object of my invention is to provide an efficient type of a spark plug for producing a spark upon passage of current through the plug, by providing a peculiarly constructed electrode which I term a "goose-neck extension electrode".

Another object of the invention is to reduce 10 and simplify sparking points, by providing a peculiarly constructed "goose-neck" electrode which produces sparks to the outside of the metal casing of the plug, said electrode being always in right firing position when 15 inserted in the plug.

With the foregoing and other objects in view, my invention comprises certain novel constructions, combinations and arrangements of parts as will be hereinafter fully 20 described, illustrated in the accompanying drawing, and more particularly pointed out in the appended claims.

In the drawing:

Figure 1 is a view in side elevation of a 25 spark plug constructed in accordance with the present invention, while

Figure 2 is a vertical central sectional view of the same.

Figure 3 is a view taken on line 3-3, Figure 2, looking in the direction of the arrows.

Figure 4 is a perspective view of the "goose-neck" electrode.

Figure 5 shows another embodiment of the "goose-neck" electrode, while

Figure 6 is a sectional view taken on line 6-6, Figure 5 and looking in the direction of the arrows.

Figure 7 is a bottom view showing the cylindrical pocket into which the head of the 40 electrode shown in Figure 5 is placed.

Figure 8 is a bottom plan view of a spark plug of a slightly modified form from the principle shown in Figures 1 and 2, while

Figure 9 is a view in side elevation of the 45 same.

Figure 10 is an enlarged fragmentary, sectional view of the cone and "goose-neck" electrode, showing the mechanical action of the conical head on the carbon in the cylindrical 50 pocket.

Referring to the drawing by numerals, 1 designates the main metal casing which is of the usual construction. A non-conductive core 2 formed preferably of porcelain is placed in the casing 1. The core 2 is provided with a central enlarged portion 3 which rests against metal gasket 4, with a somewhat similar gasket 5 placed above said gasket 4. Annular screw threaded cap ring 6 is screwed into casing 1 against gasket 5, whereby the 55 core is securely retained in the casing.

The inner end of the core is provided with a deep cylindrical pocket 7 in which is placed the conical head 8 of the "goose-neck" electrode 9. This electrode 9 is provided with a 60 threaded stem 10 that extends through core 2, as clearly shown in Figure 2. The inner broad end 11 (Fig. 4) of the head 8 bears against the inner flat end of the pocket 7, and as the head is substantially the same size in 65 diameter as pocket 7, this head acts as a cleaning plunger, for when the head is shoved outwardly, it cleans all of the carbon, grease and foreign substances out of the pocket. On the inner end of electrode 9 is formed the hook 70 or "goose-neck" 12. On the outer threaded end of stem 10 are the washers 13 and nut 14.

The end 15 of the goose-neck 12 registers with the inner edge of casing 1, forming a 75 spark gap for the current to pass from electrode 2 to the casing in an efficient manner.

It is to be noted that the conical head 8 (Figs. 2 and 10) has an arrow-like penetrating cutting action on the foreign substances in the pocket 7; said conical head 8 crushes 80 the hard, packed carbon (sticking to the sides of the pocket 7) into powder form, causing it to quickly fall from the pocket, as fully illustrated in Figure 10; said conical head 8 has only a small edge engaging the walls of 85 the pocket 7, thereby insuring of a clean cutting action and also greatly reducing the frictional engagement, without reducing its great efficiency, and the broad, inner end of the conical head produces an excellent and 90 necessary surface for the rib 16. Therefore, it will be seen that my novel and peculiarly-arranged conical head 8 has many mechanical 95 advantages over the prior art.

In Figures 5 to 9, I have shown another 100

embodiment of the principle depicted in Figures 1 to 4 in which the head 8 is provided on its inner end 11 with an elongated rib 16. 5 This rib 16 rests in one of the intersecting grooves 17 formed on the flat inner end 18 (Fig. 7) of the cylindrical pocket 7 of core 2. This groove and rib structure efficiently locks the parts together after they are assembled, keeping the point 15 of the goose-neck 10 12 in a registering position with one of the short electrodes 19 formed on the inner end of casing 1; this makes the gap somewhat more positive, causing a very efficient firing, 15 and when one electrode 19 burns off, all the operator has to do is to loosen nut 14 sufficiently to permit the rib 16 to be seated in a new position in one of the grooves 17, so as to bring end 15 in a registering position with another one of the short electrodes 19. This 20 adjusting can be continued for a long time until the short electrodes are all burnt off; this modification is a very efficient device and its long life makes it very inexpensive. 25 While I have described the preferred embodiments of my invention and illustrated the same in the accompanying drawing, certain minor alterations or changes may appear to one skilled in the art to which this invention relates during the extensive manufacture of the same, and I, therefore, reserve the right to make such changes or alterations as shall fairly fall within the scope of the appended claims. 30

35. What I claim is:

35. 1. In a spark plug, the combination with
a casing, of a core in said casing, said core
provided with a pocket, said casing provided
with a short electrode, a long electrode ex-
40 tending through said core and pocket, said
pocket and said long electrode provided with
interlocking means in said pocket for hold-
ing the long electrode in an adjusted position,
and said long electrode having its inner end
45 registering with the inner edge-end of said
casing.

2. In a spark plug, the combination with a casing, of a core extending into said casing, said core provided at its inner end with a 50 pocket having at its inner end a rib-receiving groove, an electrode extending through said core and provided with a head in said pocket, said head provided on its inner face with a rib normally seated in said rib-receiving groove, and the inner end of said electrode 55 registering with the inner end of said casing.

3. In a spark plug, the combination with a casing, of a core extending into said casing, said core provided with a pocket, said pocket provided in its inner end with a plurality of intersecting grooves, an electrode extending through said core and provided with a head in said pocket, said head provided with a broad inner end and with an elongated rib extending from said inner end, said rib nor-

mally seated in one of said grooves, and said casing provided on its inner end with a short electrode registering with the inner end of said first mentioned electrode.

4. In a spark plug, the combination with a casing, of a core extending into said casing, said core provided with a pocket and with a rib receiving grooves in said pocket, said casing provided with a plurality of short electrodes extending from its inner end, a "goose-neck" electrode in said core and provided with a rib adapted to be seated in one of said grooves for holding the inner end of said "goose-neck" electrode in a registering position with one of said short electrodes.

5. As a new article of manufacture, a spark plug, comprising a casing, a core extending into said casing, said core provided with a deep cylindrical pocket in its inner end, an electrode extending through said core and pocket, said electrode provided intermediate its length with an integral conical head in said pocket, said conical head having its narrowest end extending outwardly, said conical head bearing at its widest end against the inner end of said deep cylindrical pocket and being of substantially the same size at its inner end as the width of the pocket and fitting snugly the walls thereof, whereby the head will crush the carbon and have a free cleaning action in the deep pocket upon its entire length when reciprocated therein, and the inner end of said electrode registering with the inner end of said casing.

In testimony whereof I hereunto affix my
signature.

JOHN W. PULLIAM.
